SAFETY MECHANISM FOR CONTINUOUS
CASTING APPARATUSClarence Thulin, Waterbury, Conn., assignor to
Chase Brass & Copper Co. Incorporated, Wa-
terbury, Conn., a corporation of Connecticut

Application August 25, 1937, Serial No. 160,795

4 Claims. (Cl. 22—57.2)

This invention relates to apparatus for continuously casting metal in the form of rods, tubes, bars, or the like, and more particularly to safety features for such apparatus.

One of the objects of the present invention is to provide a continuous casting apparatus having superior means whereby the failure of such a feature of the apparatus as might cause the accidental release or dumping of molten metal from the crucible or container will automatically effect the stoppage of the apparatus.

Another object is to provide continuous casting apparatus having superior means whereby the casting apparatus may be automatically stopped in the event that a failure occurs in the casting passage or adjacent feature of the apparatus.

With the above and other objects in view, as will appear to those skilled in the art from the present disclosure, this invention includes all features in the said disclosure which are novel over the prior art and which are not claimed in a separate application.

In the accompanying drawings:

Fig. 1 is a schematic view of an apparatus illustrating an embodiment of the present invention, with the crucible or container, the casting or forming die, the cooling chamber and associated parts in vertical central section and showing the safety mechanism in its inoperative position;

Fig. 2 is a view corresponding to Fig. 1 but showing a fracture as having occurred in the retaining member of the casting-unit to thus effect the operation of the safety mechanism and the stoppage of the withdrawing-rolls; and

Fig. 3 is a transverse sectional view taken on the line 3—3 of Fig. 1.

The continuous casting apparatus herein chosen for the purpose of illustrating the present invention includes a cup-shaped container or crucible generally designated by the reference number 20 and which may be formed of any suitable material, such for instance as a clay-graphite composition commonly used in the manufacture of crucibles and the like. Such container or crucible 20 includes a substantially-flat bottom-wall 21 and an upstanding annular side-wall 22. The said container 20 rests upon a platform 23 having a vertical passage 24 therethrough in line with the central axis of the said container. Preferably the platform 23 just referred to is of a heat-insulating character and may be mounted upon any suitable support (not shown).

The bottom-wall 21 of the container or crucible 20 is provided with an axial passage 25 in which

is seated a retaining-member 26. The said retaining-member may be formed of a suitable refractory material and is provided as shown with an externally-threaded tubular shank 27 projecting below the under surface of the bottom-wall 21 of the container 20.

Threaded onto the downwardly-projecting portion of the externally-threaded shank 27 of the retaining-member 26 is the internally-threaded coupling-sleeve 28 of a cooling-chamber generally 10 designated by the reference character 29 and which is preferably formed of copper or other high heat-conductive material. Secured to one side of the cooling-chamber 29 by brazing, silver soldering or the like is a water-head 30 having a 15 water-inlet passage 31 and a water-outlet passage 32 respectively communicating with an inlet-pipe or tube 33 and an outlet-pipe or tube 34. The cooling-chamber 28 may assume a wide variety of forms and as herein shown its interior is 20 provided with a series of fins 35 to facilitate the transference of heat to the water or other coolant and is provided with a vertically-extending partition 36 which divides the interior to a degree sufficient to compel most of the coolant to flow 25 entirely around the ring-like compartment before discharging through the outlet passage 32 and tube 34.

Rigidly secured to the periphery of the cooling-chamber 29 by means of brazing, soldering or in 30 any other suitable manner is a lug 37 having a downwardly-opening threaded socket 38 therein, which latter receives the externally-threaded upper end of a vertical actuating-rod 39 having a flange-like head 40 at its lower end. The head 40 35 of the actuating-rod 39, just referred to, is normally engaged by the upper end of a vertically-adjustable thrust-screw 41 carried in one of the arms 42 of an actuating-lever, generally designated by the reference character 43, and including, in addition to the arm 42, a relatively-long oppositely-extending arm 44.

The upper surface of the outer end of the arm 44 of the actuating-lever 43 is rounded as at 45 for engagement with an antifriction roller 46 45 carried by a sear-lever 47 which is pivoted by means of a stud 48 upon a bracket 49, to which latter the actuating-lever 43, already referred to, is also pivotally connected by means of a stud 50.

The sear-lever 47 is formed at its end remote 50 from the antifriction roller 46 with a sear-nose 51 which is adapted to be engaged with the upper surface of the outer end of a pivotal switch-arm 52 which is pivotally secured at one end to the bracket 49 by means of a stud 53. The switch- 55

- arm 52 carries on its under side a circuit-closing plate 54 which is insulated from the said arm by a plate-like body of insulation 55, and which is adapted to control the flow of current between two contacts 56 and 57 which, together with the switch-arm 52 and the parts carried thereby, constitutes a control-switch generally designated by the reference character 58 and controlling the energization of a driving-motor 59.
- 10 The contact 56 of the control-switch 58 is connected by means of a wire 60 to one terminal 61 of the driving-motor 59. The opposite terminal 62 of the said motor is connected by means of a wire 63 with one of the main-line or power wires 64. The complementary main-line wire 65 is, as shown, connected by means of a wire 66 to the contact 57 of the control-switch 58, so that when the switch is in the position in which it is shown in Fig. 1, the driving-motor 59 will be energized.
- 15 Normally the container or crucible 20 is charged with molten metal 67 which flows downwardly into the upper end of the vertical casting- or forming-passage 68 of a tubular forming-die 69 which extends through the retaining-member 26 and the cooling-chamber 29 in intimate thermal contact therewith. The retaining-member 26, the cooling-chamber 29 and the forming-die 69 may, for purposes of description, be designated 20 as the "casting-unit" of the apparatus.
- 20 As the molten metal 67 passes downwardly through the forming-passage 68 in the forming-die 69, it will solidify within the said forming-passage at a point therein depending upon the speed at which the metal is withdrawn. For the 25 purpose of illustration, the solidification zone within the forming-passage 68 may be considered to be at about the point marked 70 in the accompanying drawings. It will thus be seen that molten metal 67 is solidified before emergence from the lower end of the forming-die 69, and if desired, the extraction of heat from the molten metal to effect its solidification into the solid bar 71 is effected through the lower portion 30 of the said forming-die by the cooling-chamber 29 and such additional cooling-means as circumstances may require.
- 35 The downward travel of the solidified bar 71 is effected by means of a plurality of withdrawing-rolls 72 mounted well below the cooling-chamber 29 and propelled through suitable gearing (not shown) encased within a gear-case 73 and in turn propelled by the driving-motor 59 through the intermediary of suitable mechanical 40 connections such as 74.
- 45 As before explained, the rate of withdrawal of the solidified bar 71 is such that the following molten metal concurrently flowing into the forming-passage 68 will solidify before such molten metal can emerge from the lower end of the said forming-passage.
- 50 In Fig. 1 is illustrated a normal condition of the apparatus during the casting operation, in which figure it will be noted that the control-switch 58 is held in its closed position against the tension of a spring 75 by the sear-nose 51 of the sear-lever 47, so that the driving-motor 59 is energized and the withdrawing-rolls 72 are being turned to continuously draw downwardly upon the now solidified bar or rod 71 at a pre-determined rate of speed.
- 55 Now in the event that a breakage should occur which would occasion a slight downward movement of the cooling-chamber 29 or associated parts, the driving-motor 59 will be stopped and hence the further downward travel of the now

solidified metal 71 will also be stopped, as will be presently described.

For the sake of illustration, let it be presumed that the tubular shank 27 of the retaining-member 26 has become fractured and has descended slightly in the passage 25 in the bottom-wall 21 of the container or crucible 20. Under the conditions just described, and as shown in Fig. 2, the fracture of the tubular shank 27 will permit the cooling-chamber 29 to descend to a similar 10 degree under the urge of gravity and the frictional pull of the solidified metal 71.

When the cooling-chamber 29 moves downwardly, the actuating-rod 39 will be similarly moved and will, through the thrust 41, depress the short arm 42 of the actuating-lever 43 and rock the latter about its stud 50. This rocking of the actuating-lever 43 will raise the arm 44 thereof and, through the intermediary of the parts 45 and 46, effect the lifting of the outer 20 end of the sear-arm 47, so as to turn the latter upon its stud 48 in a clockwise direction. As the sear-lever 47 is turned, as described, its sear-nose 51 will ride off of the outer end of the switch-arm 52 and permit the spring 75 thereof 25 to act and swing the said switch-arm upwardly so as to disengage its circuit-closing plate 54 from the contacts 56 and 57, thereby immediately cutting off the supply of current to the driving-motor 59 and thus, in turn, stopping further 30 downward draft upon the solidified metal 71. The parts will now have assumed the positions in which they are shown in Fig. 2.

From the foregoing, it will be seen that by means of the present invention, one of the greatest hazards to workers and equipment incident to the use of continuous casting apparatus is automatically guarded against.

When a stoppage of the apparatus has occurred, as above described, and after the breakage or defect has been remedied, the parts may all be reset as illustrated in Fig. 1 and continuous casting operations again carried on.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. Apparatus for continuously casting molten metal into solid bars, comprising: a molten-metal container; a casting-unit arranged to receive a continuous flow of molten metal from the said container and constructed to solidify the molten metal into a solid bar as it passes therethrough; withdrawing-means operating on the solid bar 60 and transmitting therethrough stress tending to rupture the casting-unit; an actuating-member mounted on a normally-fixed part of the casting-unit and displaceable from a normally-fixed position by a rupture of the casting-unit; and means constructed and arranged to be actuated by the displacement of said actuating-member, for interrupting the supply of power to the said withdrawing-means.

2. Apparatus for continuously casting molten metal into solid bars, comprising: a molten-metal container; a casting-unit having a tubular forming-die arranged to receive a continuous flow of molten metal from and extending through and beyond a wall of the said container; a cooling- 75

chamber member extending around and in heat-extracting relation to the said forming-die without the said wall of the molten-metal container, the said cooling-chamber member being supported by a portion of the said casting-unit which is disposed within and supported by the said wall of the molten-metal container; withdrawing-means operating upon and continuously withdrawing solid bar from the said forming-die; means for supplying power to the said withdrawing-means; and means normally unrelated to the continuous casting operation and suitably-constructed and arranged to be actuated by a displacement of the said cooling-chamber member responsive to a rupturing strain imposed upon the said casting-unit by the said withdrawing-means, for interrupting the supply of power to the said withdrawing-means.

3. Apparatus for continuously casting molten metal into solid bars, comprising: a molten-metal container; a cooling-chamber member depending from the bottom wall of the said container; a retaining-member mounted in a wall of the said container; means constructed and arranged to support the cooling-chamber member from the said retaining-member in depending relation to the wall of the molten-metal container; a tubular forming-die extending through the said retaining-member and cooling-chamber member and supportably engaged by both of said members in position to receive at its upper end a continuous flow of molten metal from the molten-metal container; withdrawing-means operating continuously on the solid bar issuing from the lower end of the said tubular forming-die; means for driving the said withdrawing-means; and means normally unrelated to the continuous casting opera-

tion and constructed and arranged to be actuated by a displacement of the said cooling-chamber member due to a rupturing strain imposed upon one of the said members by said withdrawing-means, to de-energize the said driving-means.

4. Apparatus for continuously casting molten metal into solid bars, comprising: a molten-metal container; a retaining-member mounted in and supported by the bottom wall of the said container; a cooling-chamber member connected to the lower end of the said retaining-member and pendently supported thereby from the bottom wall of the molten-metal container; a tubular forming-die extending through and supported by the said retaining- and cooling-chamber-members to receive at its upper end a continuous flow of molten metal from the molten-metal container to be solidified therein into a continuous bar; withdrawing-means operating upon and continuously withdrawing the solid bar from the lower end of said tubular forming-die, the said members being constructed and arranged to transmit to the said retaining-member the strain imposed thereon by the said withdrawing-means; means for supplying power to the said withdrawing-means; a normally-stationary actuating member mounted on the said cooling-chamber member; and means normally unrelated to the power-supply means during the continuous operation of the said withdrawing-means and arranged to be operated by said actuating-member accompanying a downward movement of the cooling-chamber member responsive to a rupturing strain imposed on one of the said members by the said withdrawing-means, for de-energizing the power-supplying means.

CLARENCE THULIN.
